(57) **CLAIM**
I claim, the ornamental design for an apparatus for delivery of a metered dose of granular material, as shown and described.

DESCRIPTION

FIG. 1 is a perspective view of an apparatus for delivery of a metered dose of granular material;
 FIG. 2 is a first side view thereof;
 FIG. 3 is a second side view thereof;
 FIG. 4 is a third side view thereof;
 FIG. 5 is a fourth side view thereof;
 FIG. 6 is a top view thereof; and,
 FIG. 7 is a bottom view thereof.
